US0D1028505S

(12) **United States Design Patent** (10) **Patent No.:** **US D1,028,505 S**
(45) **Date of Patent:** **** May 28, 2024**

(54) **LONG GUN CASE**

(71) Applicant: **Magpul Industries Corp.**, Austin, TX (US)

(72) Inventors: **Timothy Eric Roberts**, Broomfield, CO (US); **Clinton Wade Lynch**, Erie, CO (US); **William Furman O'Dell**, Evergreen, CO (US); **Michael T. Mayberry**, Denver, CO (US)

(73) Assignee: **Magpul Industries Corp.**, Austin, TX (US)

(**) Term: **15 Years**

(21) Appl. No.: **29/830,441**

(22) Filed: **Mar. 11, 2022**

(51) LOC (14) Cl. **03-01**

(52) U.S. Cl.

USPC **D3/254**

(58) **Field of Classification Search**

USPC D3/207, 254, 262, 273, 276, 283, 288, D3/294, 299, 302, 313; D6/515; D7/637

CPC F41C 33/06

(57) **CLAIM**

The ornamental design for a long gun case, as shown and described.

DESCRIPTION

FIG. 1 is a left, rear, top perspective view of the long gun case;

FIG. 2 is a right, front, bottom perspective view of the long gun case;

FIG. 3 is a left elevation view of the long gun case;

FIG. 4 is a right elevation view of the long gun case;

FIG. 5 is a front elevation view of the long gun case;

FIG. 6 is a rear elevation view of the long gun case;

FIG. 7 is a top view of the long gun case;

FIG. 8 is a bottom view of the long gun case; and,

FIG. 9 is a right, rear, top perspective view of the long gun case with one of two latches in an alternative position.

The shade lines in the Figures show contour and not surface ornamentation.

The broken lines showing portions of the design in all figures are included for the purpose of illustrating portions of the article and do not form a part of the claimed design.

1 Claim, 9 Drawing Sheets
